TABLE STRUCTURE

Harold Howe, Rowayton, Conn.

Application October 2, 1944, Serial No. 556,690

5 Claims. (Cl. 311--84)

1

This invention relates to a table structure.

An object of the invention is to provide a table having collapsible support means, with a minimum of parts, and a minimum of assembly operations.

Another object of the invention is to provide a table structure having collapsible supporting means which will be inexpensive and simple to make but which will nevertheless provide a solid, dependable supporting surface.

Another object of the invention is to provide a table of the kind described the legs of which are held against lateral movement both in collapsed and in supporting position.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which

Figure 1 is a plan view of the collapsed structure looking down on its under surface;

Figure 2 is a side elevation of the structure in supporting position;

Figure 3 is a plan view looking down on the under side of the structure as shown in Figure 2;

Figure 4 is a fragmentary side elevation showing the cradle member 15 mounted on the under side of the table top 10;

Figure 5 is a perspective view of the cradle member; and

Figure 6 is a fragmentary plan view of the table in collapsed position showing the relative position of one of the supporting members 16a and its cooperating stop member 20.

The table top 10 is provided with elongated spring means which serve as the only attachment between the table top and the table legs or supporting members. As illustrated herein there are two elongated spring members 11a and 11b which extend longitudinally of the table top and are preferably positioned adjacent the respective side edges of the table top. Each spring member is secured intermediate its ends to the table top 10 in any suitable way, as for example, by bolt 12 extending upwardly through the table top and retained in position by the nut 13. Preferably the intermediate or fixed portions of

2

the spring members respectively are cradled in a cradle member 15, which, as illustrated in Figure 5, extends under and across the spring member with which it is associated, and is provided with upwardly extending sides 15a forming a channel in which the spring member lies. The sides 15a of the cradle members are provided with upwardly extending prongs 15b, which are adapted to sink into and become anchored in the under surface of table top 10 when pressure is exerted on the under side of the cradle, as by tightening up nut 13 on bolt 12, which may extend through the central bore 12a provided through the cradle 15.

To the free ends of the spring members 11a and 11b support means for the table top are pivotally connected, and it will be noted that this connection is the only means for attaching the support means to the table top, hinges and the like being dispensed with. As illustrated the support means comprises two pairs of legs 16a and 16b, and 17a and 17b, respectively, the legs of each pair being preferably joined by one or more cross members c and c' respectively. The members c are somewhat shorter than the members c' so that the legs 16a and 16b, when in collapsed position, substantially parallel with the table top 10, will lie inside the legs 17a and 17b respectively. Preferably the spacing between legs 16a and 16b with respect to the spacing between legs 17a and 17b is such that the legs 17a and 17b will lie, when collapsed, on the outside of spring members 11a and 11b respectively, whereas the legs 16a and 16b, when collapsed, will lie on the inside of the spring members 11a and 11b respectively. The spring members 11a and 11b are thus conveniently connected at one end to the outside of legs 16a and 16b respectively, at pivots 18, and at the other end to the inside of legs 17a and 17b respectively, at pivots 19.

Extending transversely of table top 10 on its under side are members 20 and 21, which serve both as stop means and as position retaining means for the respective legs comprising the table support means. Member 20 is provided with the shoulders 22 positioned so that when legs 16a and 16b are in supporting position, and therefore angularly related to table top 10, they will abut against member 20 on the outside of shoulders 22 respectively, the shoulders 22 thus serving to limit and prevent lateral movement of the support means comprising legs 16a and 16b and their cross members c, while at the same time member 20 serves to limit rotational movement of the support means toward the transverse me-

dian line of the table top. Since in practice it is desirable to relate the support means to the top so that the support means at the respective ends of the table are spread apart and spaced somewhat further apart between their lower ends than their upper ends, it will be seen that in use the tendency of the support members, under load of the table top 10 and whatever objects may be placed upon it, will be to rotate inwardly, toward the transverse median line of the table top, and with this movement limited by stop members 20 and 21 respectively, a firm support for the table top is provided without hinge means interconnecting the table top and the supporting means.

Similarly member 21 is provided with the shoulders 23, which are spaced further apart than the shoulders 22 of member 20 to accord with the greater spacing between legs 17a and 17b than between legs 16a and 16b, and which serve to position legs 17a and 17b in the same way that shoulders 22 position legs 16a and 16b, and member 21 serves to limit rotation of the support means of which legs 17a and 17b are a part in the same way that member 20 limits the rotation of the support means of which legs 16a and 16b are a part.

The members 20 and 21 are also provided with longitudinally extending slots which in the embodiment of the invention illustrated herein take the form of bevels of members 20 and 21, the extent of which is indicated respectively by the dotted lines 24 and 25, which provide space of sufficient width and depth to receive therein the overlying portions of the respective leg members when they are in collapsed position. As illustrated the shoulders 22 and 23, which form a side wall for each of the said slots, or bevels, respectively, extending lengthwise of the table, serve to limit lateral movement of the legs relative to the table top, when the legs are in collapsed position, and also when the structure is on its side, as for example for storage or for transportation.

It will be seen that members 20 and 21, and the shoulders 22 and 23, coact and cooperate with the spring members 11a and 11b to position the leg members when they are in position to support the table top, and that the slots or bevels 24 and 25 respectively, together with the related shoulders, coact and cooperate with spring members 11a and 11b, when the leg members are in collapsed position, to maintain the legs in collapsed position, substantially parallel with the table top and to prevent them from flapping laterally of the table top when the legs are in collapsed position and the structure is on its side, in a vertical plane, as is the case for example when it is being carried, and when it is not in use.

It will thus be seen that there has been provided by this invention an article in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. A table structure comprising a top and support means therefor movable from a collapsed position parallel to the table top to supporting position in angular relation to the table top, said

support means being attached to the top only by elongated spring means pivotally secured at the ends to said support means respectively and secured to the table top intermediate its ends, and members extending transversely of said top and positioned with respect to said support means to provide stop means inhibiting movement of said support means in one direction from supporting position, said transversely extending members having means adapted to cooperate with said spring means to limit relative lateral movement between said support means and said top, both when said support means are in supporting position, and when said structure is collapsed and placed on its side as for storage or transportation.

2. A table structure comprising a table top, an elongated spring member extending longitudinally of the top and secured to the table top intermediate its ends, and support means for the table top pivotally secured to said spring member at its respective ends, the said pivotal connections between said spring member and said support means respectively being disposed so that said support means may be moved, from an angular relation to the top for supporting the top, to a position substantially parallel to the top within a projection of the area of the top, and means secured to the under surface of the table top serving to brace said support means both laterally and longitudinally of the top when said support means are in supporting position and to retain said support means from lateral movement when said support means are in collapsed position and the collapsed structure is substantially in a vertical plane, as for storage or transportation.

3. A table structure comprising a top, a plurality of elongated spring members extending longitudinally of the top, each being secured to the top intermediate its ends and support means for the top pivotally secured to the respective ends of said spring members, said elongated spring members being disposed adjacent the respective lateral edges of the top, and said support means comprising a plurality of pairs of legs, the legs of one pair being disposed to lie inside said elongated spring members respectively when said support means are collapsed, and the legs of the other pair of legs being disposed to lie outside of said elongated spring members respectively when said support means are collapsed, and means secured to the underside of said top each adapted to engage one of said legs both when it is collapsed and when it is in supporting position.

4. A table structure comprising a table top, support means therefor comprising legs movable from a collapsed position parallel to the table top to an angular position in relation to the table top, elongated spring means pivotally secured at the end to said support means respectively and secured to the table top intermediate its ends, said table top having transversely extending stop means having portions of reduced width each with a bevelled face aligned with the legs of said support means respectively and positioned on said table top relative to the legs of said support means so that when the legs are inclined to the table top at an obtuse angle, in position for supporting the table top, the upper ends of said legs will abut against the bevelled face of said portions of said stop means respectively, said legs adjacent their tops being of greater thickness providing inwardly extending shoul-

ders forming abutment means adapted when the legs of said support means are in collapsed position to rest against said bevelled faces of said stop means respectively with the said shoulder portions respectively in substantially abutting relationship laterally with shoulders defining an end of the said reduced portions of said stop means respectively, whereby the leg members are engaged by said stop means both when in collapsed and in support position and held against relative movement laterally.

5. A table structure comprising a table top, support means therefor movable from a collapsed position parallel to the table top to an angular position in relation to the table top, elongated spring means pivotally secured at the end to said support means respectively and secured to the table top intermediate its ends, said support means being offset on its inner surface providing an outwardly extending shoulder adjacent the 20 end of said support means which is the upper end in use, said top member having transversely extending members positioned to engage said

support means respectively both when the latter are in supporting and collapsed positions, said transversely extending members having recessed portions adapted to receive and engage the said shoulders of said support means respectively when the support means are in collapsed position, and to receive and provide a seat for the upper inner portion of said support means respectively when the latter are in supporting position.
